HEADSTOCK

Frederick S. Haas, Cincinnati, Ohio, assignor to
Cincinnati Grinders Incorporated, Cincinnati,
Ohio, a corporation of Ohio

Application December 30, 1940, Serial No. 372,263

9 Claims. (Cl. 51—237)

This invention relates to machine tools and more particularly to improvements in a headstock unit therefor.

One of the objects of this invention is to provide an improved self-contained headstock unit for machine tools.

Another object of this invention is to provide a headstock unit of the self-contained prime mover type having improved, compact mechanism for variably actuating the work driving means.

A further object of this invention is to provide an improved self-contained power driven headstock which may be selectively actuated at infinitely variable speeds as a live spindle or dead spindle headstock.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Figure 1 is a side view of the headstock unit embodying the principles of this invention.

Figure 2 is an end view of the unit shown in Figure 1 and as viewed from the left of that figure.

Figure 3 is a horizontal section on the line 3—3 of Figure 1.

Figure 4 is a section on the line 4—4 of Figure 1.

Figure 5 is a detail section on the line 5—5 of Figure 1.

Figure 6 is a detail section on the line 6—6 of Figure 3.

Figure 7 is a detail section on the line 7—7 of Figure 3.

Referring to Figure 1 of the drawings, the reference numeral 10 indicates the housing of the headstock unit upon the top of which is mounted a prime mover 11 which may preferably be an electric motor, although motors of other types may be utilized. The prime mover is attached to a slide 12 by means of bolts 13. As shown in Figure 1, the slide 12 is provided with a dovetailed guide 14 which interfits with dovetailed guide surfaces 15 formed on the top of the housing. As shown in Figure 2, the prime mover is provided with a pulley 16, which is operatively connected by a series of V-belts 17 to a pulley 53

18 keyed to the end of a shaft 19 which is journaled in the housing 10 as shown in Figure 3.

By adjusting the motor along the guideway the tension in the driving belts 17 may be adjusted. 5 After adjustment the slide is clamped in position by the hold-down bolt 20 and the clamping bolts 21.

Referring to Figure 3, the primary shaft 19 drives a secondary shaft 22 through a variable speed transmission unit comprising a first set of adjustable beveled disks 23 and 24 which are splined on the shaft 19, a second set of adjustable beveled disks 25 and 26 splined on the shaft 22, and a rigid friction ring 27 which circumscribes the pairs of disks. The disk 23 is held against axial movement by the thrust bearing 28 while the friction cone 24 is anti-frictionally journaled by the bearing 29 in the end of an adjustable sleeve 30. The sleeve may be slidably adjusted in a bore 31 formed in the wall of the housing for varying the spacing between disks 23 and 24.

The disk 26 of the driven pair is held against axial movement by the thrust bearing 31' while the disk 25 is rotatably supported by the bearing 32 in an adjustable sleeve 33 slidably mounted in a bore 34. The friction disks 24 and 25 are simultaneously adjustable to vary the speed of the device which is accomplished by virtue of the fact that they are mounted on opposite sides of the plane of rotation of the ring 27 whereby when they are both moved toward the left, for instance, as viewed in Figure 3, the effective driving diameter of the disks 23 and 24 is increased 20 while the effective diameter of the disks 25 and 26 is decreased, thus producing an increase in the rate of rotation of the shaft 22. When they are simultaneously adjusted toward the right it will be evident that a decrease in speed is effected.

35 This adjustment is effected by the mechanism shown in Figures 4 and 5. The sleeve 30 is provided with rack teeth 35 which are operatively engaged by a pinion 36 formed integral with the shaft 37 which is journaled in the housing as shown in Figure 4. This shaft has a hand wheel 38 keyed thereto at 39 and by rotating the hand wheel the sleeve 30 and cone 24 are longitudinally adjusted. The sleeve 30 is operatively connected by a rod 40 to the sleeve 33. This rod carries a radial lug 41 which fits in a radial hole 42 in the sleeve 30, and a second radial lug 43, as shown in Figure 5, which fits in a hole 44 of the sleeve 33. Thus, the sleeves 30 and 33 not only move together but in the same direction.

40 The hand wheel 38 has an annular surface 45

which may be graduated to cooperate with a fixed mark on a plate 46 to indicate the resultant speed obtained for a given position of the hand wheel. The hand wheel has a boss 47 which engages a boss 48 formed on the plate 46, and the shaft 37 is threaded at 49 for receiving a manually operated locking nut 50, which, when tightened, increases the friction between the faces of the bosses whereby the wheel is frictionally locked in any desired position. The locking nut 50 is provided with a knurled periphery 51 for facilitating rotation thereof. Thus, the variable speed unit may be adjusted to change the speed of shaft 22 and after adjustment the parts may be locked to maintain that adjustment.

The shaft 22 carries another pair of beveled disks 52 and 53 which are resiliently compressed into frictional engagement with internal, beveled surfaces 54 and 55 respectively of a rigid friction ring 56 for driving the ring. The ring has an internal annular surface 57 which frictionally engages the peripheral surface 58 of a rigid disk 59, as shown in Figure 6, for imparting rotation to the face plate 61 which is operatively connected thereto by screws 60.

The beveled disk 53 is rigidly connected to the shaft 22 by a cross pin 62 and is rotatably supported by an anti-friction thrust bearing 63 in a fixed part of the housing. The beveled disk 52 is splined on the shaft 22 and capable of axial movement relative thereto. To this end the disk 52 is fitted in the inner race 64 of an anti-friction thrust bearing, indicated generally by the reference numeral 65, while the outer race 66 of the bearing is slidably mounted in a bore 67.

A sleeve 68 is threaded at 69 in the bore and terminally engages the outer race 66. An adjusting nut 70 is also threaded in the bore and is operatively connected to the sleeve 68 by a torsion spring 71 having longitudinally extending end portions 72 and 73 projecting into the sleeve and nut respectively.

Thus, by rotating the nut, a torsion is developed in the spring, which in turn is transmitted to the sleeve, causing rotation thereof in a direction to move the sleeve toward the thrust bearing and urge the disk 52 toward the disk 53. By locking the nut against rotation with the torsion spring under load it will be apparent that the threaded connection at 69 forms a positive abutment for resisting axial retraction of the disk 52 while the torsion in the spring is continuously acting to take up any lost motion between the various parts and maintain the disk 52 in frictional engagement with the driving ring 56. The squeezing action of the disks 52 and 53 against the tapered sides of the ring not only maintains the desired frictional grip between the surfaces, but also develops a component in a radial direction on the ring opposite to its point of contact with the disk 59, thereby developing the desired frictional grip between the surfaces 51 and 58.

The nut 70 is provided with a series of radial holes 74 as shown in Figure 4 for receiving a small operating lever 71' by which the nut is rotated. After the desired torsion is obtained in the spring by clockwise rotation of the nut, the lever is inserted in one of the radial holes whereby it may rest against the abutment as shown in Figure 4 to prevent counterclockwise creep of the nut.

The disk 59 serves as a hub for the face plate 61 and is provided with a bore 74 for receiving an anti-friction bearing 75 by which the face plate and disk are supported for rotation by

the cylindrical surface 76 of the headstock spindle 77. The spindle, in turn, is supported by anti-friction bearings 78 and 79 for rotation in the housing. A work supporting center 80 is inserted in one end of the spindle while the other end of the spindle is provided with a knurled hand wheel 81 by which the spindle may be rotated independently of the face plate. Means are provided whereby the spindle may be connected to the face plate for rotation therewith whereby the headstock operates as a live center headstock, or the spindle may be locked against rotation while the face plate revolves about it, resulting in a dead center headstock. The connection is obtained by threading a circular plate 82 on the nose of the headstock at 83 and providing a notch 84 in the periphery of the plate for selective engagement by a lug 85 carried by the face plate.

This lug is integral with a radially slidable support 86 for the lug, the support being movable in a dovetailed guide 86', and a set screw 87 is threaded in the support for locking it either in a position with the lug engaging the slot, or with the lug out of engagement with the slot. A spring 88 is interposed to act on the support in a radially outward direction so that by simply loosening the locking bolt 87 disengagement will be effected between the lug 85 and the slot 84. A limiting pin 89 may be inserted in the guideway for limiting the outward movement.

The face plate is provided with the usual driving pin 90 for engaging the work piece dog for imparting rotation thereto and it should now be evident that this rotation may be imparted regardless of whether the center is a live center or a dead center.

After the headstock has been operated as a dead center headstock, the hand wheel 81 may be utilized for rotating the spindle to bring the slot 84 into alignment with the lug 85 for operation as a live center headstock.

In order to insure against rotation of the spindle when operating as a dead center headstock, a stop pin 91 is mounted in the wall 82. This pin has a beveled end 93 for engaging a bevel-sided keyway 94 formed in the spindle 77, the bevel sides serving to take up lost motion. A spring 95 continuously urges the pin radially inward while a cross pin 96 serves to lock the pin 91 out of engagement with the slot. By turning the pin 91, the cross pin 96 may be aligned with notches to permit inward movement of the pin 91.

There has thus been provided an improved self-contained headstock which is compact in construction, variable as respects speed, and which may be utilized as a live or dead spindle headstock, rendering it especially suitable for precision machine tools such as grinding machines.

What is claimed is:

1. In a headstock unit for grinding machines and the like, the combination of a housing having a work driving member journaled therein, a disk operatively connected to said member, a power driven shaft journaled in said housing, a prime mover operatively connected for driving said shaft, said shaft having a pair of oppositely beveled disks mounted thereon and operatively connected thereto, and a rigid member for transmitting motion from the shaft to the work driving member, said rigid member circumscribing all of said disks and having a pair of beveled surfaces for frictionally engaging the beveled surfaces of said pair of disks and a third surface

for frictionally engaging the periphery of the disk associated with said work driving member.

2. In a headstock unit, the combination of a housing having a work driver journaled therein, a power operable shaft journaled in said housing, a pair of beveled disks mounted on said shaft, means for urging said disks toward one another, a driven disk associated with the work driver and having a cylindrical peripheral surface, a ring circumscribing all of said disks and having a pair of beveled surfaces for engaging the beveled surfaces of said pair of disks, and a third surface connecting said bevel surfaces and adapted to frictionally engage said cylindrical surface for the purpose of transmitting motion from said shaft to said work driver.

3. In a headstock unit for machine tools, the combination of a housing having a work driving member journaled therein, of means for effecting a non-chattering rotation of said member, comprising a prime mover mounted on the housing, a drive shaft journaled in the housing, motion transmitting means coupling the prime mover for rotation of the shaft, an intermediate shaft journaled in the housing, a variable speed friction drive connection between said shafts, and means connecting the second shaft for rotation of the member including a pair of oppositely beveled disks mounted on the intermediate shaft, a cylindrical disk associated with the member, a rigid drive ring surrounding all of said disks and having a pair of beveled surfaces engaging the beveled surfaces of said pair of disks and a third surface for frictionally engaging the periphery of the cylindrical disk, and means for continuously urging said pair of disks toward one another to maintain a uniform friction between the surfaces of said disks and ring.

4. In a headstock unit, the combination of a housing having a work driver journaled therein, a pair of shafts journaled in said housing, a prime mover operatively connected for driving one of said shafts, an infinitely variable speed mechanism interconnecting said shafts, adjusting means for changing the speeds of said mechanism, means connecting the driven shaft to the work driver including a pair of beveled disks splined on the driven shaft, a driven disk operatively connected with the work driver and having a cylindrical peripheral surface, a ring circumscribing all of said disks and having a pair of beveled surfaces engaging the beveled surfaces of said pair of disks and a third surface interconnecting said beveled surfaces for engaging the cylindrical surface of the driven disk, and resiliently operable means for urging said pair of disks into frictional engagement with the beveled surfaces on said ring to establish a driving friction therebetween and to establish a radial component on said ring to maintain friction between the ring and the cylindrical surface of the driven disk.

5. A headstock unit for a machine tool comprising a housing, a work driver journaled in the housing, and means for effecting a smooth non-chattering rotation of the work driver at variable speeds including a drive shaft and a driven shaft journaled in the housing, a pair of opposed beveled driving discs carried by the drive shaft, multiple pairs of opposed bevel driving discs carried by the driven shaft, a rigid driving ring frictionally connecting the drive discs of the drive shaft with one set of drive discs on the driven shaft for transmission of power from the driving to driven shaft, means for positively relatively

adjusting the discs of the connected pairs to vary the rate of speed transmission from the driving to driven shaft, a second rigid driving ring interconnecting the work driving member and another of the sets of opposed beveled driving discs on the driven shaft, and means for automatically urging the said latter pair of discs one toward the other to maintain proper power transmitting tension between said discs, the ring and the work driving member.

6. A headstock unit for a machine tool comprising a housing, a work driver journaled in the housing, and means for effecting a smooth non-chattering rotation of the work driver at variable speeds including a drive shaft and a driven shaft journaled in the housing, a pair of opposed beveled driving discs carried by the drive shaft, multiple pairs of opposed bevel driving discs carried by the driven shaft, a rigid driving ring frictionally connecting the drive discs of the drive shaft with one set of drive discs on the driven shaft for transmission of power from the driving to driven shaft, means for positively relatively adjusting the discs of the connected pairs to vary the rate of speed transmission from the driving to driven shaft, a second rigid driving ring interconnecting the work driving member and another of the sets of opposed beveled driving discs on the driven shaft, means for automatically urging the said latter pair of discs one toward the other to maintain proper power transmitting tension between said discs, the ring and the work driving member, the work driving member having a driving disc peripherally formed for internal engagement with the circumscribing driving ring and said driving ring having an inner face formed for cooperation with the disc and adjacent beveled faces for cooperation with the beveled discs on the driven shaft.

7. A headstock unit for a machine tool comprising a housing, a work driver journaled in the housing, and means for effecting a smooth non-chattering rotation of the work driver at variable speeds including a drive shaft and a driven shaft journaled in the housing, a pair of opposed beveled driving discs carried by the drive shaft, multiple pairs of opposed bevel driving discs carried by the driven shaft, a rigid driving ring frictionally connecting the drive discs of the drive shaft with one set of drive discs on the driven shaft for transmission of power from the driving to driven shaft, means for positively relatively adjusting the discs of the connected pairs to vary the rate of speed transmission from the driving to driven shaft, a second rigid driving ring interconnecting the work driving member and another of the sets of opposed beveled driving discs on the driven shaft, means for automatically urging the said latter pair of discs one toward the other to maintain proper power transmitting tension between said discs, the ring and the work driving member, the work driving member having a driving disc peripherally formed for internal engagement with the circumscribing driving ring and said driving ring having an inner face formed for cooperation with the disc and adjacent beveled faces for cooperation with the beveled discs on the driven shaft, and means for varying the urge of said ring engaging discs toward each other whereby to vary the latter pressural engagements of the driving discs with the beveled faces of the ring and the radial pressure of the ring against the disc on the work driving member.

8. A headstock structure of the character de-

scribed including a housing, a work engaging spindle journaled in the housing, a work driving member journaled on the spindle for rotation therewith and with respect thereto, said driving member including a disc having an outer cylindrical surface, a pair of opposed bevel driving discs journaled in the housing in juxtaposition to the spindle and spaced to receive the disc therebetween, a rigid driving ring of greater width than the thickness of the disc circumscribing the disc of the work driver and the beveled discs, said ring having beveled faces in interfitting engagement with the opposed faces of the beveled discs and an inner annular surface conforming to and in engagement with the periphery of the disc on the work driving means, means for urging the beveled discs one toward the other frictionally to engage the opposite faces of the ring, and a driven shaft in driving engagement with the discs whereby to impart a smooth rotative movement to the work driving member by way of the rigid ring and the disc on said member.

9. A headstock structure of the character described including a housing, a work engaging spindle journaled in the housing, a work driving member journaled on the spindle for rotation therewith and with respect thereto, said driving

5 member including a disc having an outer cylindrical surface, a pair of opposed bevel driving discs journaled in the housing in juxtaposition to the spindle and spaced to receive the disc therebetween, a rigid driving ring of greater width than the thickness of the disc circumscribing the disc of the work driver and the beveled discs, said ring having beveled faces in 10 interfitting engagement with the opposed faces of the beveled discs and an inner annular surface conforming to and in engagement with the periphery of the disc on the work driving means, means for urging the beveled discs one toward the other frictionally to engage the opposite faces of the ring, a driven shaft in driving engagement with the discs whereby to impart a smooth rotative movement to the work driving member by way of the rigid ring and the disc on said member, said driven shaft having a lateral extension, an 15 additional pair of opposed beveled power transmitting discs journaled in the housing and having hub portions receiving the extension of the shaft, driving connections between said disc and the shaft, and means for transmitting variable speeds to the shaft by way of said discs for actuation of the work driving member.

FREDERICK S. HAAS.
